G. H. LEWIS,
COLLAPSIBLE CORE,
APPLICATION FILED AUG. 24, 1917.

1,281,600.

Patented Oct. 15, 1918.

UNITED STATES PATENT OFFICE.

GEORGE H. LEWIS, OF CHICOPEE FALLS, MASSACHUSETTS, ASSIGNOR TO THE FISK RUBBER COMPANY, OF CHICOPEE FALLS, MASSACHUSETTS, A CORPORATION OF MASSACHUSETTS.

COLLAPSIBLE CORE.

1,281,600.

Specification of Letters Patent.

Patented Oct. 15, 1916.

Application filed August 24, 1917. Serial No. 137,950.

To all whom it may concern:

Be it known that I, GEORGE H. LEWIS, a citizen of the United States of America, residing at Chicopee Falls, in the county of

5 Hampden and State of Massachusetts, have invented certain new and useful Improvements in Collapsible Cores, of which the following is a specification.

This invention relates to collapsible cores, 10 such, for example, as are adapted for use in the manufacture of the outer casings or shoes of pneumatic tires and more particularly to improved means for holding the several sections of the core in assembled relation.

In general, the present invention contemplates the securing of the sections in assembled relation by the circumferential contraction of a plurality of arcuate members 20 contractible at a plurality of points, and contractible means being distributed in a definite manner for the purpose of moving the several core sections into close abutment and into exact concentrical relation more 25 efficiently than has been possible heretofore, so far as I am aware.

According to one feature of the invention, a plurality of arcuate members are provided, one for each of the relatively large 30 sections of the core, which members completely encompass arcuate shoulders on the large sections and overlap and partially encompass arcuate shoulders on the adjoining smaller sections, and means are provided in 35 each of the smaller sections to engage the ends of adjacent members and draw them toward one another. The distribution of the arcuate members and their contractible means in the manner defined is characterized 40 in that the smaller core sections may be readily moved into exact concentrical relation with the larger sections, and the latter may be effectively drawn into close abutment with the smaller sections without interfering with the movement of the latter 45 into accurate concentrical position.

According to another feature of the invention, each arcuate member is provided with means to insure its location on the relatively large core sections in a definite pre-

determined position and in a position best calculated to coöperate with the contracting means which are definitely located on the smaller core sections.

According to another feature of the invention, the several arcuate members, in order to perform their function, are inserted in arcuate grooves, which open only on one side face of each core section, and means are provided, whereby the several members may 60 be conveniently removed from the grooves and said means are accessible from that face of the assembled core on which the groove opens.

Other features of the invention will appear in the following description and in the illustrative embodiment of the invention in the accompanying drawings, in which:

Figure 1 is an elevational view of a collapsible core embodying the invention; 70

Fig. 2 is a cross sectional view taken on the line 2—2 of Fig. 1;

Fig. 3 is a fragmentary circumferential section taken on the line 3—3 of Fig. 1;

Figs. 4 and 5 are cross sectional views 75 taken on the lines 4—4 and 5—5, respectively, of Fig. 1;

Fig. 6 is a fragmentary sectional elevational view illustrative of the dowel connections between adjoining core sections; and 80

Fig. 7 is a fragmentary end elevation of one of the core sections showing the dowel.

Referring to these drawings, the assembled core, shown in Fig. 1, is an annulus which is made up of a plurality of sections 85 10 and 11 in the now well known way for the purpose of permitting convenient removal of the core from the tire shoe after the curing operation. The number of sections, which go to make up the core, may be 90 varied within limits as desired, but preferably the illustrated subdivision is employed wherein two relatively large sections 10 and two relatively small sections 11 are employed. As illustrated the end faces of 95 the smaller sections 11 are substantially parallel, but they may be otherwise arranged if desired for the only essential is that the sections 11 may be withdrawn radially inward from the tire shoe.

The cross sectional shape of the core sections is clearly shown in Fig. 2, and the contour of the outer portions of the core may obviously be varied as desired depending upon the desired conformation of the inner surface of the tire shoe. The core sections are preferably made hollow, as illustrated in Fig. 2, although such construction is not absolutely essential. Each 10 core section is provided with an inner arcuate flange 13, in which is provided an arcuate groove 14 opening on one side only of the flange. The several core sections 10 and 11 are adapted to abut, as shown in Fig. 1, to 15 form a complete annular core ring and, when the sections are drawn into precise abutment, by means to be described, the ends of the grooves 14 coincide and a true circular groove is formed. At each joint between 20 abutting sections, a dowel 15 is provided on one section, as best shown in Fig. 7, and this dowel is adapted to fit into a suitable recess on the other section, as clearly shown in Fig. 6. The dowel connection described prevents lateral displacement of adjoining core sections.

As a means for drawing the several core sections into close abutment and precise concentrical relation, two substantially semi-circular members 16 are provided which, as shown in Fig. 2, are adapted to fit in grooves 14 of the flanges 13. Each member 16 has a pin 17 radially projecting therefrom, and the pins 17 are adapted to fit in slots 18 formed in the sections 10, as best shown in Fig. 4. The provision of pins 17 and slots 18 makes it necessary that the members 16 be always placed in grooves 14 in a definite circumferential position. They insure that 30 the ends of adjacent members 16 overlap the small core sections 11 equally for a purpose to appear. Located centrally in the groove 14 of each of the smaller sections 11 and projecting laterally therefrom is a stud bolt 19, which is fixed to flange 13, as shown in Fig. 3, and the adjacent ends of the members 16 are held by the pins 17 and slots 18 an equal 35 distance from the stud 19. Each end of each member 16 is recessed to form a cam surface 20, and adjacent surfaces 20 converge outwardly toward the exposed face of the members. A plate 21 having a central aperture to receive stud 19 is formed with oppositely inclined cam surfaces 22 to coöperate 40 with the surfaces 20. When a nut 23 on stud 19 is turned down the coacting cam surfaces cause the ends of members 16 to be drawn toward one another in a manner which will be clearly obvious from Fig. 3. 45 Each member 16 is furthermore provided with a short groove 24 in its inner periphery and, by means of the positioning devices 17 and 18, groove 24 is caused to register, as shown in Figs. 1 and 5, with a recess 50

formed in an outer face of the flange 13 of 65 each core section 10.

With the parts assembled as in Fig. 1, the core may be taken apart by removing nuts 23 and plates 21 and thereafter removing members 16. The latter operation may be 70 conveniently accomplished by inserting a tool, technically known as a spade, in recess 24 and prying or "spading" the member out of its groove. Once the members 16 are removed, the two smaller sections 11 may be 75 withdrawn radially inwardly from the tire shoe, leaving dowels 15 held to the larger sections 10. The latter sections may then be readily removed thereafter from the tire shoe.

In assembling the core, the sections 10 and 80 11 are fitted together into approximately concentrical and abutting relation. The members 16 are then laid into the grooves 14 of the sections 10 and 11 and necessarily positioned so that pins 17 lie in slots 18. The plates 21 are then slipped over studs 19 and nuts 23 are tightened to force cam surfaces 22 into engagement with surfaces 20 and continued tightening of nuts 23 causes the 90 ends of members 16 to be drawn toward one another. Preferably the nuts 23 are alternately turned down by increments, so that the ends of the members 16 are drawn together equally on each side of the core. 95 Thus the several sections may be securely held together by the binding force of members 16 applied upon the circumferential shoulder formed by the inner peripheral walls of grooves 14.

The members 16, however, accomplish other important functions, namely, the drawing together of the several core sections so that they exactly abut and are drawn into exact concentrical relation. The core, 100 by the mere assembly of parts with the members 16 in place, is not suitable for the desired use, although by these operations the sections are positioned approximately in abutment and in concentrical relation. It is 110 quite necessary, in order to avoid the formation of fins, that the sections exactly abut. The drawing together of the ends of members 16 by the means described, however, results in drawing the ends of the core sections 115 into intimately close abutting relation and in true concentrical relation so that the outer periphery of the assembled core is practically as smooth as if the core were made in one piece.

An important feature of the invention is that the members 16 are carried by the relatively large sections, and the tightening devices by the relatively small sections. By this arrangement, the two 125 forces which result from the drawing together of members 16 are best adapted to accomplish their intended function.

Thus, one force acts to draw the sections into abutment, and this force should not be so great as to prevent the other force from moving the two smaller sections inwardly 5 into precise concentrical relation. By the arrangement illustrated, the act of drawing the ends of members 16 toward one another results in a much greater movement of the free ends of the members than of the central portions of the latter. The tendency 10 thus is to move the relatively small, and therefore light, sections 10 bodily inward into concentrical relation with the larger sections rather than to bodily shift the latter. The larger sections are moved simply 15 to draw their ends into abutment with the small sections. To apply the greater force to the work of drawing the large sections into abutment with the small sections prevents 20 to a large extent the movement of the sections into concentrical position by the lesser force.

The importance of the arrangement described appears with added force when it 25 is considered that the cores are subjected to hard and rough usage. Such cores are assembled and taken apart repeatedly and in such operations are handled none too gently. They are subject to rapid wear and the 30 means for tying the several sections together should be designed to operate none the less effectively on account of wear. Thus, the grooves and members 16 become worn so that the original fit, no matter how closely 35 made, is not retained. When the members 16 no longer closely fit the grooves, the assembly, prior to drawing the members 16 together, may not be so closely approximate as originally when the parts closely fitted. 40 That is, the smaller sections 11 may have to be shifted radially inward a greater amount than formerly to effect the desired accurate concentrical positioning. If the greater force tends to prevent the smaller 45 force from effecting this increased degree of radial movement of the smaller sections, it will be seen that an accurately assembled core could be had only with the greatest difficulty. Where, however, the force acting 50 to accomplish the radial movement of the smaller sections is superior by reason of the arrangement described, this difficulty no longer exists and parts may be assembled into accurate relation despite the wear of 55 parts. The ends of members 16 would simply be drawn closer together than before but would still act on the inner circumferential surface of the groove 14, and, although the latter is of less radius, due to 60 wear, the accurate concentrical positioning of the sections is nevertheless effectively accomplished.

The invention has been described herein for illustrative purposes, but the scope of

the invention is defined by the appended 65 claims rather than by the foregoing description.

What I claim is—

1. A collapsible core, comprising, a plurality of sections each having an arcuate shoulder, said sections adapted to abut with one another to form an annular core and said shoulders to form a continuous circular ring, a plurality of arcuate members each of which is arranged to wholly encompass the shoulder of only one section and to partially encompass the shoulders of each of the adjacent sections, whereby each member overlaps two joints only of the core ring, there being at least two of said members and so 80 arranged that spaces are left between the adjacent ends of the members, and means carried by each of said adjacent sections to connect the adjacent ends of said members and draw them together to force the several sections into concentrical and abutting relation.

2. A collapsible core, comprising, an annular ring made up of relatively small and relatively large sections and providing when 90 assembled a continuous circumferential slot opening to a side face of the core, a plurality of arcuate members to fit into said slot, means including parts attached to the smaller sections to connect the adjacent ends of said members and draw them toward one another, and means to position said members circumferentially in the larger sections so that each member overlaps the joint between a 95 large and two small sections and so that the ends are properly positioned to coöperate with the first-named means.

3. A collapsible core, comprising, an annular ring made up of alternate small and large 105 sections and having in a side face a continuous circumferential slot, an arcuate member for each large section adapted to fit in said groove and overlap a part of each adjacent small section, cams formed adjacent the ends 110 of each member, and a device on each small section having means to coöperate with each pair of adjacent cams to draw the sections into abutting and concentrical relation.

4. A collapsible core, comprising, an annular ring made up of alternate small and large sections and having in a side face a continuous circumferential slot, an arcuate member for each large section adapted to fit in said groove and overlap a part of each adjacent small section, means on each small section to draw the ends of adjacent members toward one another to move the several sections into abutment and into true concentrical relation, and coöoperating means 120 formed in each ring and each large section to permit the former to be conveniently removed from the latter.

5. A collapsible core, comprising a sectional

annular core ring having a continuous circumferential shoulder and made up of a plurality of alternate large and small core sections assembled in abutting relation, the 5 smaller core sections adapted to be moved radially of the ring to collapse the latter, arcuate members, one for each large core section, adapted to encompass said shoulder, each member adapted to be definitely lo-

cated with its mid portion on a large section and its free ends partially overlapping the adjacent small sections, and means in fixed relation on each small section to engage the ends of adjacent members and draw them toward each other to move the several 15 sections into concentrical and abutting relation.

GEORGE H. LEWIS.
